UNITED STATES PATENT OFFICE.

ALBERT F. RUTHVEN, OF CLEVELAND, OHIO.

STALLION-SHIELD.

1,317,107.

Specification of Letters Patent. Patented Sept. 23, 1919.

Application filed February 20, 1918. Serial No. 218,237.

To all whom it may concern:

Be it known that I, ALBERT F. RUTHVEN, citizen of the United States, residing at Cleveland, in the county of Cuyahoga and State of Ohio, have invented certain new and useful Improvements in Stallion-Shields, of which the following is a specification.

This invention relates to stallion shields. 10 The object of the invention is to provide an improved shield which effectively discourages excitation or erection, which is cleanly and sanitary, which is easily applied and adjusted, and which is not injured and will 15 not injure the stallion when lying down. Further objects of the invention are in part obvious and in part will appear more in detail hereinafter.

In the drawings, which represent one embodiment of the invention, Figure 1 is a diagrammatic perspective view, illustrating the shield and its harness in position on the stallion; Fig. 2 is a broken out plan of the shield in folded position and Fig. 3 is a 25 longitudinal section thereof, showing the shield extended in operative position.

Referring first to Figs. 2 and 3, the shield comprises a suitable flat body portion 1 which lies in horizontal position when on the stallion, and which is supported by a suitable harness as hereafter described. This body portion may be made of any suitable material having requisite strength, but preferably is so constructed as to be sanitary and to prevent the collection of dirt and filth. In the drawings the body portion 1 is a border or frame consisting of sheet metal bars or members 2 which may be formed from a plate and are therefore continuous around the entire body, or which may consist of separate pieces rigidly secured to each other at the angles of the frame. This frame 2 is preferably covered to prevent injury to the stallion such as by the jacket 3 made of leather or other suitable material. Frame 2 serves to support the open mesh screen 4 made for example of large mesh heavy galvanized wire screen, the openings in which allow free passage of urine. The body portion 1 with its screened floor is made wide enough to prevent any possible escape of the stallion's part downwardly or laterally, as a consequence of which any extension by the stallion will 50 cause engagement with the guard 5 at the front portion of the horizontal body. The

back portion of the body may be tapered, as shown in Fig. 2, to fit better between the legs.

The guard 5 may be made of any suitable material, for example, metal, although in the particular form shown in the drawings it is made of one or more plies of leather, the inner or rear surface thereof being provided with a series of spaced points or projections which may be either sharp or blunt as desired. These points or projections for example may be formed by tacks whose heads lie between the leather plies of the guard 5. The normal position of the guard 5 when 70 on the stallion is shown in Fig. 3, in which position any extension or erection by the stallion meets with the deterring effect of the projections 6 and thereby effectively discourages excitation or erection and possible resulting loss of strength and vitality. 75

The guard 5 is preferably connected to the body portion 1 so as to be capable of being tilted relatively thereto or of folding down into superposed or parallel relation therewith. This may be accomplished by a suitable hinge joint between the guard and body portion or the guard may be attached to the body portion by thongs or lacing members 7, the yield in which and the flexibility of the guard 5 enable it to be folded out or extended to the operative position in Fig. 3.

The shield is supported on the stallion by any suitable harness, that shown in the drawings consisting of a neck strap 10 adjustable as to length, a belly strap 11 having an elastic portion 12 attached to the front edge of the body portion 1, a back strap 13 connecting the neck strap 10 to the back pad 14, a crupper or tail strap 15 connected at one or several points to the rear edge of the body portion 1, and two side supports 16 extending from the back pad 14 to the side edges of the body portion and 95 guard. Preferably the side supports 16 have two or more branches 17 connected to the side edges of the body portion and a third branch 18, preferably elastic, connected to the upper side edges of the guard 5. 100 All straps may be adjustable as to length by the provision of suitable buckles or other devices as is usual.

When the shield is adjusted on the stallion, as indicated in Fig. 1, the guard 5 is 110 extended to an inclined relation with the base 1, forming an open pocket or recess 20

2
of considerable lateral extent so as to with certainty receive and offer resistance to any extension by the stallion. The screened bottom 4 also prevents escape downwardly. 5 When the stallion lies down the guard 5 folds down into parallel or superposed relation with the body, the prongs 6 entering the meshes of the screen 4 and therefore being protected or covered up. They also 10 extend away from the body of the stallion and consequently will not injure him. Furthermore the flat form of the shield prevents it from being crushed when the animal lies down. The shield is very effective and is 15 also cleanly and sanitary.

What I claim is:—

1. A stallion shield, comprising a foraminous body portion, a guard connected to the front edge thereof and capable of being tilted relatively thereto or folded into parallel relation therewith, and means for supporting said shield on the stallion with said guard extending upwardly from the body portion. 20
2. A stallion shield, comprising a foraminous body portion, a guard connected to the front edge thereof and capable of being tilted relatively thereto or folded into parallel relation therewith, means for support- 25

ing said shield on the stallion with said guard extending upwardly from the body portion, and a series of spaced projections on the rear face of said guard. 30

3. A stallion shield, comprising a foraminous body portion, a guard connected to the front edge thereof and capable of being tilted relatively thereto or folded into parallel relation therewith, and a suitable harness for supporting said shield upon the stallion with the guard extending upwardly from the body portion and including straps connected to the side edges of the body portion and guard. 35

4. A stallion shield, comprising a flat body portion having a rigid frame and a foraminous body portion, a guard attached to the front edge of said frame and extending upwardly therefrom and capable of being tilted relatively thereto or folded into parallel relation therewith, a series of projections upon the rear face of said guard, supporting straps attached to the side edges of said body portion, and flexible supporting straps attached to the upper side edges of said guard. 40

50 In testimony whereof I affix my signature.

ALBERT F. RUTHVEN.
